(57) **CLAIM**

We claim the ornamental design for a personal stimulation device, as shown and described.

DESCRIPTION

FIG. 1 is a perspective view of the top side of our personal stimulation device;

FIG. 2 is a perspective view of the top side thereof from the back end;

FIG. 3 is a top view thereof;

FIG. 3A is a close-up of the portion identified as 3A in FIG. 3;

FIG. 4 is a bottom view thereof;

FIG. 4A is a close-up of the portion identified as 4A in FIG. 4;

FIG. 5 is a front end view thereof;

FIG. 5A is a close-up of the portion identified as 5A in FIG. 5;

FIG. 6 is a back end view thereof;

FIG. 7 is a side view thereof (with the opposite side being a mirror image thereof); and,

FIG. 8 is a cross-section of a perspective view of the top side of our personal stimulation device taken along line 8-8 of FIG. 1 thereof.

The broken lines shown and the cross-sectional hatching in the drawings illustrate portions of our personal stimulation device that form no part of the claimed design. Specifically, the cross-sectional view shown in FIG. 8 is provided for reference only, and the cross-sectional view does not form any part of the claimed design.
